[57] **CLAIM**

The ornamental design for a drop detector, substantially as shown and described.

DESCRIPTION

FIG. 1 is a top perspective view of a drop detector, in an operative or tube clamping position, embodying our new design with the fragmentary portion of a tube shown in broken lines for illustrative purposes only, FIG. 2 is a top perspective view of the drop detector, in its normal or nonoperative position,

FIG. 3 is a top plan view thereof,

FIG. 4 is a front end view thereof,

FIG. 5 is a back end view thereof,

FIG. 6 is a side view thereof, and

FIG. 7 is an opposite side view thereof.

FIG. 1**FIG. 2****FIG. 4****FIG. 3****FIG. 5****FIG. 6****FIG. 7**
